REUBEN A. DAHLQUIST, OF CHICAGO, ILLINOIS

DESIGN FOR A GAME BOARD

Application filed April 25, 1932. Serial No. 43,604. Term of patent 14 years.

To all whom it may concern:

Be it known that I, REUBEN A. DAHLQUIST, a citizen of the United States, residing at Chicago, in the county of Cook and State of Illinois, have invented a new, original, and ornamental Design for Game Board, of which the following is a specification, reference being had to the accompanying drawing, forming a part thereof.

Fig. 1 is a top plan view of the game board,

Fig. 2 is a sectional view showing the ornamental configuration of the game board when viewed from the edge, with two of the sockets at the right used to receive marbles and with the marble groove shown in section at the left edge.

I claim:

The ornamental design for a game board as shown and described.

In witness whereof, I hereunto subscribe my name, this 21st day of April, 1932.

REUBEN A. DAHLQUIST.
